CLAIM

The ornamental design for an edging unit for garden landscaping, as shown and described.

DESCRIPTION

FIG. 1 is a top perspective view of an edging unit for garden landscaping showing my new design, the broken-line showing of the tree being for illustrative purposes only and forming no part of the claimed design; FIG. 2 is a top plan view thereof; FIG. 3 is a bottom plan view thereof; FIG. 4 is a rear elevational view thereof; FIG. 5 is a front elevational view thereof; and FIG. 6 is a side elevational view thereof, the side opposite being identical in appearance.

FIG. 1

FIG. 3

FIG. 2

FIG. 4

FIG. 5

FIG. 6
